PAINTING APPARATUS

Filed April 5, 1927

UNITED STATES PATENT OFFICE

PAUL P. WALKER, OF DOWNERS GROVE, ILLINOIS, ASSIGNOR TO CHICAGO, BURLINGTON & QUINCY RAILROAD COMPANY, OF CHICAGO, ILLINOIS, A CORPORATION OF ILLINOIS

PAINTING APPARATUS

Application filed April 5, 1927. Serial No. 181,216.

My invention relates to painting apparatus and has for its principal object, the provision of an improved simplified painting machine.

Another object is to provide a painting machine adapted to be operated by its engagement with the article being painted.

Another object is to provide a simplified means for applying a protective paint coating to board lumber.

Another object is to paint board lumber during the normal handling thereof and without the expenditure of comparatively greater time than is required for handling such lumber without painting.

Other objects and features will appear from the consideration of the following detailed description taken with the accompanying drawings in which—

Fig. 1 is a side elevational view partially broken away to conserve space, showing one form of my painting machine, and

Fig. 2 is a plan view of the machine with the superstructure thereof removed.

My invention has been directed principally to the painting of railroad car lumber. This lumber has in the past been stored at the car shops without any protection. By means of my invention, I paint three sides of the boards as they are removed from the car and take practically no more time to paint and pile the lumber, than has been taken in the past to simply remove it from the cars and pile it for storage.

As the board lumber is removed from a car, it is placed upon suitable runways where it proceeds by gravity or by being pushed by workmen to the position in which it is to be stored. At the end of the runway, I insert a painting apparatus which requires no power connection and which is adapted to supply paint to the boards as they pass in contact therewith. No extra handling is required and the boards not only receive a protecting coating but this coating also acts as a primer or first coat, therefore saving a great deal of time in the painting operation after they have been applied to the sides and ends of a car.

Referring now to the drawings, I illustrate a usual form of runway adapted to con-

vey the board lumber to a storage position. The runway comprises a framework 10 having upper longitudinal members 11—11 in which are journaled the axes of a plurality of rollers 12—12. A bracing rod 13 extends between uprights of the frame and the longitudinal members 11.

My painting machine is adapted to be mounted on a section of this conveyor framework and in the drawings I show it so mounted. I can of course employ an entirely separate framework but it is apparent that my purpose will be served more readily by adopting the structure shown.

A lower reservoir 16 is secured between the two members 11, in any suitable manner, so as to depend below the upper level of the framework. An upper reservoir 17 is secured to a pair of supporting brackets 18 which are also secured on the members 11. 70 A rotary brush 19 is mounted to revolve upon an axis 21 so that its lower surface projects into the paint in the reservoir 16 and its upper surface is slightly above a line coinciding with the top of the rollers 12. The rotary brush 19 is constructed of simple and inexpensive materials. I have employed for this purpose, a wooden roller with a comparatively heavy Brussels carpet secured on the outside thereof with the bristles extending outwardly.

It is apparent, a board passing over the roller 19 will pick up a coating of paint therefrom, but in order to obtain the best results I provide guides for the board.

The centering guides are two in number and comprise spring guides 22 provided with triangular plates 23 which are pivoted to studs 24 secured in the longitudinal frame members 11. The triangular sections 23 have a plurality of holes 25 arranged at equal distances from the pivot 24, and are adapted to cooperate with a single aperture 26 in the members 11 for regulating the positions of the guides 22. By withdrawing pins 27, the triangular sections 23 may be moved about the pivots 24 until another one of the holes 25 registers with the aperture 26 in the members 11. The pin is then reinserted and the guide has an adjustment for a different size 100

of board. The guides are exactly alike except for being reversed, and each is preferably set when a different size board must be accommodated.

6 I also provide means for holding the board firmly against the roller 19. On each longitudinal frame member 11, a bell crank lever 28 is secured on a pivot 29 and a roller 31 is rotatably secured between the two bell 70 cranks. A guide 32 is secured to the frame and has a slotted portion in which one arm of the bell crank is adapted to extend. A coil spring 33 has one end secured to the forward end of the bell crank lever and the 75 frame, so that at all times a downward pressure of roller 31 takes place. The pressure roller 31 therefore serves to keep the board at all times in engagement with the roller brush 19; while a roller 34 identical with the 80 roller 12 described above, serves to prevent too great a pressure of the board against the roller brush 19.

8 The sides of the board are painted by roller brushes 35—35 secured on arms 36 which are pivoted to the main frame 37. The two arms 36 have small end extensions between which a tension spring 38 is secured, thereby tending at all times to bring the two side brushes 35 together. But it is not advisable to permit the brushes 35 to come too close to each 90 other as they may then interfere with the passage of the board therethrough. Accordingly on each arm 36, there is pivoted a rod 41 which is reciprocable in a guide 42. The 95 rod 41 has a plurality of vertically disposed apertures 43 adapted to receive a pin whereby the inner movement of the arm 36 is limited, by outside movement thereof permitted to any extent within the limits of the 100 design.

40 Each of the brushes 35 is supplied with paint from the upper reservoir 17 through a vertically disposed pipe 45. Midway of the pipe 45, a valve 46 is inserted having a valve 45 operating handle 47. A block 48 extending transverse of the machine forms a connection with each one of the valve handles 47 and has, extending therethrough, a trip bar 49. A board passing between the brushes 35 is 105 adapted to engage the lower end of the trip bar 49 and by moving said bar slightly it opens the valves 46 and permits a flow of paint to the brushes 35. The brushes being held in engagement with the sides of the 110 boards, apply a coating of paint thereto.

55 A pair of wiping brushes 51 is secured to the bracket support 18 for the purpose of wiping the excess paint off the edges of the board after the paint has been applied by the 115 roller brushes 35. A pair of wiping brushes 60 52—52 is supported in brackets 53—53 secured to the frame and adapted to wipe the excess paint from the under side of the board.

65 Paint is supplied to the bottom reservoir

16 from the reservoir 17, the drippings from the brushes 35 being sufficient to keep the lower reservoir well supplied with paint at all times. Paint is manually supplied to the upper reservoir whenever required. An 70 over-flow pipe 54 secured through the bottom of the reservoir 16 maintains the paint therein at a constant level. The paint flowing through the top of the over-flow pipe 54 is trapped in a suitable receptacle and returned to the reservoir 17. A valve 55 in the over-flow pipe can be closed during the time that the receptacle is removed from beneath the over-flow pipe 54 to be emptied 75 into the upper reservoir. 80

A roller 56 identical with the rollers 12 is provided at the output end of the machine to facilitate passage of the boards being painted. A drop board 57 facilitates the removal of the board for the purpose of 85 piling.

The boards may be propelled through the machine by hand, but when the conveyor is positioned on a slant and the boards travel 90 propelled by gravity, they may carry themselves entirely through the machine without the necessity of applying any hand pressure. 95

Claims:

1. In a painting machine an upper paint reservoir, a lower paint reservoir, mechanism 95 for guiding an article to be painted between said reservoirs, a rotary brush for removing paint from the lower reservoir and applying it to a portion of the article, a pair of side rollers adapted to apply paint to other portions of the article, and means for supplying paint to the side rollers from the upper reservoir only when the article is passing therethrough.

2. In a painting machine an upper paint 105 reservoir, a lower paint reservoir, mechanism for guiding an article to be painted between said reservoirs, a rotary brush for removing paint from the lower reservoir and applying it to a portion of the article, a pair of rollers 110 adapted to apply paint to the sides of the article, a pair of pipes extending from the upper reservoir to the side rollers whereby paint may be supplied to said rollers, valve means for normally cutting off the flow of paint in said pipes, and a connection from the valve means adapted to be engaged by the article as it passes therebetween for operating said valve means and causing a flow 115 of paint to said side brushes as the article is 120 passed therebetween.

3. A machine for applying paint to three 125 sides of board lumber, said machine comprising a framework with cross rollers thereon along which the board is adapted to be propelled, a paint reservoir supported by the frame in line with the rollers but below the same, a paint reservoir, supported above the frame in line with the lower paint reservoir, a pair of guides for centering the board on 130

- the rollers, a rotary roller brush adapted to remove paint from the lower reservoir and apply it to the under side of the board, a spring pressed roller for pressing the board against said roller brush, a pair of rotary brushes for applying paint to the side edges of the board, a pair of pipes leading from the upper reservoir to the brushes, a valve in each pipe, a handle connection from the valves projecting in the path of the board, so that the board in passing engages said connection and opens the valves, and means for closing the valve when the board has passed completely through the machine.
- 15 4. A machine for applying paint to three sides of board lumber, said machine comprising a framework with cross rollers thereon along which the board is adapted to be propelled, a paint reservoir supported by the frame in line with the rollers but below the same, a paint reservoir, supported above the frame in line with the lower paint reservoir, a pair of guides for centering the board on the rollers, a rotary roller brush adapted to remove paint from the lower reservoir and apply it to the under side of the board, a spring pressed roller for pressing the board against said roller brush, a pair of rotary brushes for applying paint to the side edges of the board, a pair of pipes leading from the upper reservoir to the brushes, a valve in each pipe, a handle connection from the valves projecting in the path of the board, so that the board in passing engages said connection and opens the valves, means for closing the valve when the board has passed completely through the machine and means for wiping the painted board lumber at the sides and bottom after the paint has been applied thereto.
- 40 5. A machine for applying paint to three sides of board lumber, said machine comprising a framework with cross rollers thereon along which the board is adapted to be propelled, a paint reservoir supported by the frame in line with the rollers but below the same, a paint reservoir, supported above the frame in line with the lower paint reservoir, a pair of guides for centering the board on the rollers, a rotary roller brush adapted to remove paint from the lower reservoir and apply it to the under side of the board, a spring pressed roller for pressing the board against said roller brush, a pair of rotary brushes for applying paint to the side edges of the board, a pair of pipes leading from the upper reservoir to the brushes, a valve in each pipe, a handle connection from the valves projecting in the path of the board, so that the board in passing engages said connection and opens the valves, means for closing the valve when the board has passed completely through the machine, a pair of brushes arranged one at each side of the frame and beyond the rotary brushes for ap-
- plying paint to the side edges of the board, said brushes adapted for wiping and smoothing the painted edges, and a pair of brushes disposed beyond the rotary roller brush for wiping and smoothing the paint applied to the bottom of the board, both of such pairs of brushes being disposed within the periphery of the lower reservoir.
- In witness whereof, I hereunto subscribe my name this 1st day of March, 1927.
